APPARATUS FOR PACKAGING MATERIALS

Theodor M. Reimers, Chicago, Ill., assignor to
Standard Cap and Seal Corporation, Chicago,
Ill., a corporation of Virginia

Application May 26, 1947, Serial No. 750,417

19 Claims. (Cl. 226—82)

1

This invention relates to method and apparatus for packaging materials and more especially to a method and means for packaging foodstuffs and the like whereby the same are incased in hermetically sealed wrappers or containers.

The invention embraces a method for inclosing foodstuffs or similar materials in a wrapper or container and subjecting the filled wrapper to a source of subatmospheric pressure and subsequently sealing the wrapper or container to maintain a subatmospheric pressure therein.

An object of the invention is the provision of an apparatus for subjecting a plurality of wrappers or containers filled with materials to subatmospheric pressure and sealing the filled wrappers or packages while the same are subjected to or under the influence of such reduced pressure.

Another object of the invention is the provision of an apparatus for impressing subatmospheric or differential pressure upon the interior of a flexible wrapper and sealing the wrapper to maintain subatmospheric pressure therein whereby the wrapper is held in close contact with the materials contained therein under the influence of atmospheric pressure.

Another object of the invention resides in the provision of an apparatus for impressing subatmospheric pressure upon filled containers of flexible material in which the containers are carried in chambers formed in a relatively movable magazine having several sections, and in which the arrangement is provided with mechanism brought into operation by movement of the magazine to bring a section into operative sealing position for automatically initiating the operation of a container vacuumizing and sealing cycle.

Another object of the invention resides in the provision of an apparatus for vacuumizing and sealing filled containers in which the movement of a container carrying magazine section into operative position initiates mechanism for effecting the vacuumizing and sealing operations, the apparatus being provided with electrical and mechanical mean for establishing and initiating the operation of various mechanisms and controls in proper sequential relationship for effecting the several steps in vacuumizing and sealing the containers.

Another object of the invention is the provision of a container carrying magazine embodying several container supporting sections which are arranged for consecutive movement to vacuumizing and sealing position, the sections being so arranged that during vacuumizing and sealing op-

2

erations being carried out upon one group of containers supported in one section, the operator may deposit filled containers in another magazine section preparatory to subsequent vacuumizing and sealing operations upon the containers supported in the succeeding magazine section, thus increasing the efficiency of a packaging machine of this character.

Another object of the invention resides in the provision of means for interrupting the vacuumizing and sealing operations in the event that for any reason an insufficient vacuum is impressed upon the filled containers.

Still another object of the invention resides in the provision of electrically energized means for sealing a thermo-responsive or heat sealable wrapper or container during the impression of a subatmospheric pressure or substantial vacuum upon the containers.

Still a further object of the invention is the provision of a magazine section for a container vacuumizing and sealing machine provided with chambers adapted to accommodate molds or receptacles of different sizes in order to adapt the mechanism for operation upon filled containers of various sizes and shapes.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is a vertical longitudinal elevational view of the apparatus for vacuumizing and sealing filled containers, certain parts being shown in section;

Figure 2 is an end elevational view of the machine shown in Figure 1 with housing portions shown in section;

Figure 3 is a vertical sectional view taken substantially on the line 3—3 of Figure 1;

Figure 4 is a vertical sectional view through a valve construction incorporated in the vacuum line, the section being taken substantially on the line 4—4 of Figure 2;

Figure 12 is a horizontal detail sectional view taken substantially on the line 12—12 of Figure 1;

Figure 13 is an isometric view showing a type of mold arranged to be disposed in container supporting magazine and is configurated to accommodate a particular size of container, and

Figure 14 is a diagrammatic view of the electrical circuits and control mechanism for the apparatus.

While I have illustrated the apparatus of my invention as utilized for vacuumizing and sealing flexible wrappers or containers adapted to contain foodstuffs and the like, it is to be understood that I contemplate the use of the method and apparatus of my invention wherever the same may be found to have utility.

Referring to the drawings in detail and particularly with respect to Figures 1 and 2, the apparatus is inclusive of a base or base plate 10 upon which is mounted upright frame or frame members 11 and 12, the uprights being secured to base plate 10 by means of bolts 14. The frame member 11 is formed with pairs of laterally spaced bosses 15, and the frame member 12 is similarly formed with pairs of laterally spaced bosses 16. The pairs of bosses 15 and 16 are formed with vertical bores adapted to slidably receive pairs of vertical rods or shafts 21 and 22. The upper extremities of the rods 21 and 22 extend into bores formed in boss portions 24 integrally formed at the ends of a member 25 extending between the pairs of rods. The rods 21 and 22 are fixedly secured to the bridge member 25 by means of pins 26 or other suitable retaining means. Slidably mounted upon the rods 21 and 22 is a head structure 29 which contains a chamber adapted to be connected with a vacuum producing means, the chamber containing a thermo-sealing means, the construction and arrangement of which will be hereinafter described. The sealing head is supported upon the rods 21 and 22 by means of collars 31 secured to the rods.

The arrangement of my invention is inclusive of a means or magazine 30 adapted to contain a plurality of filled wrappers or containers upon which vacuumizing and sealing operations are to be performed. In the embodiment illustrated, the magazine 30 is inclusive of a plurality of sections 37 which are arranged for successive movement into container vacuumizing and sealing position. The frame members 11 and 12 are each provided with a boss 32 which is bored to receive a bearing member 33, the bearing members forming journals in which is rotatably mounted a shaft 34, the latter providing a supporting means for the magazine 30. Mounted upon the shaft is an abutment collar 35 pinned or otherwise secured thereto in order to prevent endwise movement of the shaft 34 in a left hand direction as viewed in Figure 1. Mounted upon the shaft 34 is a pair of spaced hub members or blocks 36

which are of polygonal shape and having facets equal to the number of magazine sections 37 comprising the container carrying means. In the embodiment illustrated there are five magazine sections so that the hub members 36 are each formed with five sections supporting facets. Each of the magazine sections 37 is formed with boss portions 43 adapted to fit upon one pair of aligned facets of the hub members as shown in Figure 1, the sections being secured to the hub members by means of bolts 45. As illustrated in Figure 1, the foremost magazine section is shown broken away to facilitate illustrating the magazine section supporting means.

Each magazine section is formed at its upper portion with a laterally extending flange 46 which is adapted to be engaged by a gasket 68 carried by the head 29, in a manner and for a purpose to be hereinafter explained. Each magazine section 37 is formed with a plurality of chambers 49 which are adapted to individually receive mold blocks 50, the latter being of a shape to accommodate flexible filled wrappers or containers of a particular size. One of the mold blocks of the character used is illustrated in Figure 13. Each of the mold blocks is interiorly formed with a chamber or space 51 of a shape to accommodate a particular size of container, it being understood that different mold blocks having different shaped interiors may be utilized to accommodate wrappers or containers of different sizes and shapes. By this means the machine or apparatus may be used for vacuumizing and sealing many different sizes and shapes of packages by simply utilizing molds 50 having recesses or chambers of proper size and shape. Each chamber 49 in a magazine section is formed at its mouth portion to receive a plate 52 which is held in place by means of screws 53, the plates serving to hold the molds 50 in position in the magazine section. I have found that mold blocks fabricated of wood have been satisfactory, but it is to be understood that the individual mold blocks may be formed of any suitable plastic, metal or other suitable material.

As shown in Figure 7 the upper portion of each magazine section is formed with two series of projecting bosses 56 and 57 which are bored to receive rods 58 and 59. The rod 58 forms a pintle for hingedly supporting the members or flaps 60, there being a flap 60 for each chamber in a magazine section. The flaps are each provided with a longitudinal extending platen or pad 61 preferably formed of rubber or other suitable or yieldable material, the same forming a backing pad or bar for supporting or engaging portions of the packaging container during sealing operations in a manner to be hereinafter explained. The shaft 59 forms a pintle for hingedly supporting an elongated flap or member 63 which extends substantially the length of a magazine section as shown in Figure 1. The outer longitudinal edge of the flap or member 63 is formed with an offset portion 64 which engages the upper ends of the wrappers or containers and overlaps the terminus portion of each of the flaps 60 as shown in Figure 7.

In utilizing the apparatus of my invention, an envelope, wrapper or container enclosing a commodity and which is to be vacuumized and sealed is preferably fabricated of flexible material which may be readily and quickly sealed to provide an hermetically closed package. I have found that an envelope or container formed of material having thermo-plastic or thermo-sealable prop-

erties is satisfactory for the purpose. There are several materials available which are thermo-sealable, as for example compounds of wax and rubber, materials fabricated of vinyl resins, and a material known as Pliofilm. A container or wrapper C of the character having heat sealable properties and of a strength to withstand comparatively high atmospheric pressures when the interior of the container is impressed with a sub-atmospheric pressure is illustrated in Figure 7. The filled container C is disposed in a position in which the piles or laminae of material at the mouth of the container pass through the space between the flaps 60 and 63 and overlie the resilient pads 61, the container being in this position immediately prior to the movement of the head 29 into engagement with the magazine section and prior to the initiation of the sealing operation.

In carrying out the vacuumizing process, I have provided means for impressing a sub-atmospheric or differential pressure upon the chambers in a magazine section, which low pressure or substantial vacuum will be effective upon the interior of the filled containers. In this connection the head 29 is formed with a rectangular member 67 having a hollow interior or chamber arranged to be connected to a source of subatmospheric pressure. The lower face of the member 67 is provided with a recess or channel of rectangular configuration within which is adapted to be disposed a resilient gasket or sealing element 68. When the member 67 is moved downwardly, the gasket 68 seats upon the upper surface of the flange 46 so as to form a hermetic joint for the interior of the magazine section in alignment with the head 29. Thus when reduced pressure is effective within the interior of the member 67, such reduced pressure is impressed upon the contents of the containers in the magazine section which is in engagement with the gasket 68.

The chamber or hollow interior of the member 67 is arranged to be connected to a suitable source of subatmospheric pressure or vacuum producing means. To this end an L-shaped fitting 70 is connected by means of a flexible conduit 71 to a second fitting 72, the latter being connected by means of a tube or conduit 73 with a valve housing 75. The valve housing 75 is provided with a tubular fitting 76 adapted to be connected to a vacuum pump or means for producing a subatmospheric pressure (not shown). The valve housing 75 is fixedly mounted upon bosses 77 formed on the base plate 10. The interior mechanism of the valve is illustrated in Figure 4, and includes a rotary valve member 79 which is preferably of frusto-conical formation and is adapted to be received in a seat of reciprocal shape. The end of the housing adjacent the larger end of valve member 79 is closed by means of a plate 80 held in place by screws 81. The valve member 79 is axially bored to accommodate an expansive coil spring 82 for urging the valve member 79 into proper contact with the valve seat. The valve member 79 is formed with a central bridge or vane 83 which forms channels or recesses 84, the latter being adapted to cooperate with tube 73, the tube 76 and a vent or bleed opening 85 for alternately maintaining the vacuum or subatmospheric pressure effective upon the head 29 and at a predetermined period during the cycle of operations, to interrupt the impression of reduced pressure or vacuum on the head and vent the same to the

atmosphere to "break" the vacuum. The tube 73 is also connected by means of a duct or tube 87 with a pressure responsive valve 91 which may be of any conventional construction. The valve 91 contains switch mechanism (not shown) responsive to a pre-determined vacuum or subatmospheric pressure existent in the system arranged to complete the motor circuit for initiating further operation of the machine during vacuumizing and sealing operations in a manner to be hereinafter explained.

The apparatus is inclusive of a thermo means for heat sealing the laminae of the wrappers or containers after a pre-determined degree of reduced pressure or vacuum is existent in the containers. To accomplish this purpose there is movably disposed within the interior chamber of member 67 an elongated sealing bar 88 which is arranged to be heated by suitable means. As shown in Figure 7 the sealing bar 88 is provided with a surface or shoe portion 89 which is angularly disposed or canted into parallelism with the upper surface of the resilient backing members 61 so as to provide a full area of contact or close engagement for the laminations of the container to effect a thermo-seal between these laminations.

The sealing bar 88 is of hollow configuration and the interior of the bar is arranged to receive and accommodate electric heating units 90 which are connected to a suitable junction plate 92 which, in turn, is connected to a source of electrical energy. As shown in Figure 1, an end of the member 67 is provided with a thermo-responsive element 94 connected to an indicator 95 for indicating the temperature of the heat sealing bar. The heating elements are connected with a suitable pilot light 96 for giving a visual indication when the elements are energized.

The bar 88 is supported from bridge member 25 by means of vertical rods 97 which have threaded portions 98 engaging in member 99 which are held in place by plates 100. The rods 97 extend upwardly through bosses 101 which are provided with stuffing or sealing glands 102 so that air will not seep into the head 29 which condition would otherwise impair the formation of vacuum or reduced pressure. The upper portion of the rods are threaded, and mounted upon the threaded portions above and below the member 25 are adjusting members or collars 104 which are threadedly received upon the rods. The collars 104 are provided with set screws 105 for locking the collars in adjusted position. By means of this adjustment the relative position of the heat sealing bar 88 may be regulated so that the shoe portion 89 is brought into contacting engagement with the laminations of the flexible container disposed in overlapping relationship on the resilient pads or bars 61 during a sealing operation.

Mounted upon the head 29 is a suitable plate or frame 107 provided with an indicator or gage 108 connected by means of a fitting 109 with the chamber in member 67 for indicating the pressure in the interior of the member 67.

The movable mechanism of the apparatus is driven by a motor 111, the pedestal portion of which is mounted upon and secured to the base plate 10. Extending axially of the motor 111 is a housing 114 which encloses suitable reduction gearing (not shown) operated by the motor 111. The gearing in housing 114 drives a shaft 115 at a comparatively slow speed. Mounted upon the shaft 115 is a sprocket 116 which is con-

nected by means of a chain 117 with a second sprocket 118, the latter being of comparatively large size and is mounted upon a shaft 119. Secured to the upright frame member 12 is a bracket 120 held to the frame member by means of bolts 121. The shaft 119 is journaled in bearings 122 carried respectively in bracket 120 and a boss 123 formed integrally with the upright frame member 12.

The sprocket 118 is provided with a hub 126 supporting a disc-like member or cam 127 by means of bolts 125. The disc 127 may be adjusted about the axis of shaft 119 by reason of slots (not shown) contained in the disc and accommodating locking bolts 125. The disc 127 is provided with a land or dwell 128 and a second land or dwell 129 for controlling the operation of a micro-switch 130. The housing containing the micro-switch 130 is mounted upon an arm 131 of bracket 120. The housing of micro-switch 130 supports an arm 132 from which depends a swingable member 133 to the lower extremity of which is journaled a cam follower or roller 134, the latter being arranged for engagement with the periphery or cam surface of the disc-like member 127. The micro-switch is provided with a slidable plunger 135 and surrounding the plunger 135 is a coil spring 136 which is disposed between the arm 133 and a nut 137 which secures the member 132 to the housing of the micro-switch. This spring serves to urge the arm 133 in a direction to bring the roller or cam follower 134 into engagement with the periphery of the disc 127. The function of this mechanism will be hereinafter explained.

The apparatus is inclusive of means for actuating or moving the head 29 vertically to bring the latter into engagement with a magazine section and for moving the sealing bar 88 into engagement with the laminations of the containers or wrappers during the heat sealing operations. This means is inclusive of a cam member 139 having a hub portion 140 secured to the shaft 119 by means of a key 141. The member 139 is provided with an axially extending peripheral flange portion 143 and a second axially extending flange or raised portion 144 spaced from the flange portion 143. The inner wall 146 of flange 143 and outermost wall 147 of the raised portion 144 form cam surfaces for controlling or guiding the radial movement of a roller or cam follower 148. As shown in Figure 10 the cam walls or surfaces 146-147 are provided with inwardly directed cam surfaces 150-151, dwells 152-153, canted surfaces 154-155, another set of cam surfaces 156-157 and a further set of angularly disposed or canted surfaces 158-159.

The cam follower or roller 148 is journaled upon a pin 162 secured to the mid-portion of an arm or lever 163, the latter being provided at one end with a bore adapted to receive a pin or stub shaft 164, the pin 164 being journaled in bearings mounted in a pedestal or support 165. The pedestal is secured by means of bolts 166 to bosses 167 formed on the base plate 10. The lever 163 is arranged for oscillatory movement about the axis of the stub shaft 164. The lever 163 is pivotally connected at its other extremity by means of a shaft or bolt 169 to the lower end of the link or member 170. The upper end of the link 170 is pivotally connected by means of a bolt or shaft 171 with the end of an arm 172. The arm 172 is received upon one end of a shaft 174 and is fixedly secured thereto by means of a key 175. Mounted upon shaft 174 are spaced

arms 176-177, as shown in Figure 1, which are secured to the shaft by means of keys 178, one of which is shown in Figure 12. Mounted upon each of the pairs of vertical rods 21 and 22 are connecting members 180 and 181, the members being provided with bosses which are bored to accommodate the vertically extending rods which are pinned thereto by means of dowels 182. The extremities of arms 176-177 are bored to accommodate bolts or threaded members 183, the threaded portions of which extend into threaded openings provided in the respective central portions of members 180 and 181. In this manner the arms 176 and 177 are pivotally connected to the members 180 and 181 respectively.

The walls 146 and 147 of cam member 139 connecting cam surfaces 150-151 with cam surfaces 158-159 are formed as radii generated about the axis of shaft 119 so that during this peripheral distance of the cam, the cam follower or roller 148 remains in a relatively static position so that there is no relative vertical movement imparted to the head 29. The several cam surfaces disposed in the remainder of the member 139 cause vertical movements of the head 29 in a manner and for purposes to be hereinafter explained.

The member 139 is integrally formed with spaced L-shaped projections 186-187, each of which is provided with a threaded opening to receive a bolt 188 upon which are respectively mounted rollers 189 and 190. As shown in Figure 4 the vacuum controlling valve 79 is provided with a tenon 193 upon which is mounted member 194 of general configuration of a Geneva wheel. During rotation of the member 139, the rollers 189 and 190 successively engage the member 194 to move the valve member 79 through an angular distance of approximately 90 degrees to periodically render the vacuum effective and ineffective to the head 29.

Means are also provided for locking the magazine with a magazine section in vacuumizing and sealing position and for initiating a vacuumizing and container sealing cycle. In the embodiment illustrated, I have provided foot operated means for effecting a release of locking means for the container magazine. The frame member or upright 12 is provided with boss portions 197 and 198 which are bored to accommodate a horizontally disposed shaft 199. Mounted upon a projecting extremity of shaft 199 is a foot lever or treadle 200 having a foot pad portion 201. The member 200 is urged toward its uppermost position under the influence of a coil spring 202. Also mounted upon the shaft 199 intermediate the bosses 197, 198 is an arm 203 pinned or otherwise secured to the shaft. The arm 203 is pivotally connected at its extremity by means of a pin 204 with a vertically extending bar or link 205, the upper end of which is pivotally connected to a lever or member 206 by means of a pivot pin 207 as shown in Figures 3 and 5. Also pivotally supported upon pin 207 is a pendulated dog or latch member 208. Secured upon the shaft 34 is a disc-like member 210 formed with spaced projections or teeth 211, the number of projections being equal to the number of magazine sections, viz., in the embodiment shown there being five magazine sections and five projections. The latch member 208 is arranged to cooperate with the projections 211 to prevent inadvertent reverse movement of the container magazine by the operator. The member 206 is pivoted upon a bolt 214

which is threaded into an opening in the upright frame member 12. The bolt 214 provides a pivot about which the member 206 is adapted to oscillate. Also fixedly mounted upon shaft 34 is a disc-like member 215 which is provided with five equally spaced recesses or depressions 216 arranged on the periphery of the disc. The member 206 is provided with a detent or projection 217 fixedly carried by member 206 which is adapted to seat in a recess 216 to retain a magazine section in proper position to accommodate the head 29.

Mounted adjacent the lever member 206 is a plate 219 arranged for vertical slidable movement with respect to the frame member 12. The plate is configurated with slots 220 and 221 adapted to respectively receive bolts 222 and 223, the slots permitting limited vertical movement of the plate 219. Secured to the plate 219 is a micro-switch 224 having a switch plunger 225. Also secured to the micro-switch housing is a bracket 226 retained in place by means of screws 227. The bracket 226 has a depending portion 228, the lower end of which is provided with a bolt 229 upon which is journaled a roller 230 as shown in Figure 5. The roller 230 is disposed in the path of projections 211 formed on disc 210 and is adapted to be moved in vertical direction during rotation of disc 210 under the influence of the projections 211. In this manner the plate 19, micro-switch 224 and bracket 226 are periodically moved in a vertical direction. A coil spring 238 disposed between the head of bolt 222 and plate 29 provides a frictional component sufficient to retain the plate in its uppermost position until the same is moved downwardly by means hereinafter described. Mounted upon shaft 34 is an arm or trigger 232, said arm being arranged for oscillatory movement about the axis of shaft 34. The member 206 is provided with an angularly disposed slot 233 adapted to accommodate a roller 234 journaled upon a suitable bolt or pin 235 threaded into an opening in the trigger or member 232. The upper portion of arm 232 is formed with an anvil 236 which is adapted, under certain conditions of operation, to engage and depress the micro-switch plunger 225. The portion of arm 232, immediately beneath anvil 236, is recessed as at 237 to permit retractive movement of plunger 225 without re-engaging the member 232. The frame upright 12 is formed with a boss portion 240 having threaded openings arranged to receive a bolt 241. The member 206 is provided with a slot 242 to accommodate the bolt 241, the latter serving to guide the member 206 during oscillatory movements thereof.

Means are provided for periodically moving the slidable plate 219 and elements carried thereby to their lower-most positions. Rod 22 is formed with a threaded opening adapted to receive a bolt 244. The bolt 244 supports an L-shaped bracket or pawl 245, the latter being arranged to oscillate about the axis of bolt 244. The bracket 245 is provided with a shoulder 246 which is arranged whereby upon downward movement of rod 22, the same will engage a projection or lug 248 carried by member 226. The swinging movement of pawl 245 is limited in one direction by means of an abutment or pin 249 carried by the supporting rod 22. Limiting means is also provided for disengaging shoulder 246 from lug 248 on member 226 so as to prevent damage to the mechanism in the event that the rod 22 moves downwardly an abnormal distance during

10

sealing operations. To this end the frame member 12 is provided with a stop member 250 arranged in a path of an arm or ledge 251 integrally formed on bracket 245. Thus when the bracket 245 in engagement with lug 248 has moved downwardly a predetermined distance, the arm 251 will strike the stop member 250 causing bracket 245 to swing in a counter-clockwise direction as viewed in Figure 5 to disengage shoulder 246 from lug 248. By this means downward movement of the slidable plate 219 and parts carried thereby is thus limited.

Electrical connections are made to a junction box 254 mounted upon the upright frame member 12 as shown in Figure 1. A diagrammatic view of the electrical circuits is shown in Figure 14 in which the power line indicated at 260-261 enters the junction box 254. One side of the power line is connected by means of a conductor 262 with the motor 111, the other conductor 263 from the motor being connected with the microswitch 130. The microswitch 224 is connected in parallel with microswitch 130 by means of current conductors 265 and 266. The other side of the power line is connected by means of conductor 267 with the microswitch 130 and conductor 265. The vacuum actuated switch mechanism 91 is shunted across the circuit leading to the microswitch 130. Also arranged in parallelism with the vacuum operated switch 91 is an emergency starting switch 268. The heating elements 90 contained within the sealing bar 88 are connected to one side of the power line by means of conductors 269, 270 and 271. A pilot light 96 is intercalated in circuit with the heat elements. The conductor 267 is connected to a thermo-controlling switch 274 by means of conductor 275, the switch 274 being connected to the heating elements 90 by conductors 273 and 276 for maintaining a pre-determined temperature of the heating elements.

The series of operations and the sequence thereof in vacuumizing and sealing a set of filled containers in one magazine section is as follows:

The containers of heat sealable flexible material which have been previously filled with foodstuffs or other commodities to be sealed therein are delivered by means of a chute (not shown) to a position adjacent the machine. The operator is preferably seated so as to be in a position to conveniently place filled containers in the magazine sections 37 and also to rotate the magazine about the axis of shaft 34. The operator first places filled containers in the magazine section 37 that extends angularly upwardly and to the left as viewed in Figure 2. The operator swings the members 60 and 63 about their hinges to open position exposing the mouths of molds 50. The operator then inserts a filled container into each mold block in one magazine section. As each container is placed in a mold, the operator swings the hinged member 60 into the position shown in Figure 7, and arranges the projecting laminations of the container so that they overlie the resilient pad 61 on member 60. After the several molds of a section receive the filled containers, the operator swings the hinged member or retainer 63 to the position shown in Figure 7, causing the laminations of each container to lie in parallelism with pads 61 as shown in Figures 2 and 7.

The operator then grasps the next succeeding magazine section, viz., as shown in Figure 2, being the section extending downwardly and in a left hand direction, and depresses the foot lever or

treadle 200. This movement of the lever 200 moves link 205 downwardly, oscillating member 206 about the pivot shaft 214 in a counter-clockwise direction as viewed in Figures 3 and 5. This action elevates the pawl or detent 217 out of a recess 216, thus releasing the magazine for rotation about the shaft 34. After this release has been effected, the operator manually rotates the magazine in a clockwise direction as viewed in Figure 2 to bring the section provided with filled containers into registration with the sealing head 29. This movement of the magazine rotates the disc 210 to bring the next succeeding projection 211 into engagement with the roller 230 carried by the depending portion 228 of bracket 226. The projection 211 acts on the roller 230 causing the plate 219 and parts carried thereby to move upwardly. When the operator depresses the treadle 200, the arm 232 is swung in a clockwise direction, as viewed in Figure 5, under the influence of the treadle spring 202, causing pawl or detent 217 to seat in the adjacent recess 216 and lock the magazine in position. As the bar 206 returns to its normal position as in Figure 5, the arm or trigger 232 moves counter-clockwise to bring the anvil portion 236 thereof into engagement with the plunger 225, depressing the latter to close the motor circuit through this switch. Thus with micro-switch 224 closed, the motor is energized causing cam member 139 to be rotated through the sprockets 116, 118 and chain 117. The rotation of cam member 139 causes the cam surface 150 shown in Figure 8 to move the cam follower or roller 148 downwardly to move lever 163 in a clockwise direction as viewed in Figures 2 and 8. This action causes downward movement of link 170 to oscillate arm 172 and rotate shaft 174 causing downward movement of arms 176, 177 and corresponding downward movement of members 180-181 and rods 21 and 22 to move the bridge member 25 downwardly. The downward movement of bridge member 25 compresses the springs 28 causing the head 29 to move downwardly with the rods 21 and 22 until the sealing gasket 68 engages the platen or flange 46 formed on the magazine section so as to effect an hermetic seal between such magazine section and the head 29. As soon as the head 29 is in its lowered position with the gasket 68 in engagement with the magazine section, the roller 189, by reason of rotation of cam member 139, engages one of the projections of the Geneva wheel or member 194 to rotate the vacuum controlling valve 79 through an angular distance of 90 degrees so as to render the vacuum which is effective in the tube 76 from a continuously operating vacuum pump to be impressed through tube 73 to the hollow interior of the member 67 forming a part of the head structure 29. The subatmospheric pressure or vacuum in the chamber is then effective throughout the major part of a revolution of cam member 139 to reduce the pressure in the containers and container molds disposed in the magazine section in engagement with the head 29.

The motor continues to rotate while the vacuum or reduced pressure is being set up in the head 29, molds and containers until those portions of surfaces 146 and 147 of member 139 immediately adjacent cam surface 158, 159 are still

acting on the cam roller 148. When the disc 127 has rotated to bring the dwell 129 adjacent microswitch 130 the latter switch is opened. During the period in which the bridge member 25 and heads 29 are moved downwardly, the pawl or latch member 246 engages the lug 248 on bracket 226 to move the latter including plate 219 and microswitch plunger 225 out of contact with the anvil 236 on the trigger member 232. This action opens the microswitch 224 so that when microswitch 130 is opened in the manner above described, both microswitches are "opened" and the motor ceases rotation. The impression of vacuum or reduced pressure continues however until the desired degree of pressure is secured. When this condition is attained, the vacuum or pressure controlled switch 91 is closed to again complete the motor circuit and start the motor 111. Restarting the motor causes member 139 to rotate, bringing cam surface 158 to contact with collar 148 to move the latter further downwardly. This results in also moving rods 21, 22 and bridge member 25 further downwardly. As the bridge member 25 carries the sealing bar 88 through the medium of the supporting rods 97, the sealing bar is thus moved downwardly bringing the pressure shoe 89 thereof into contact with the laminations of the filled containers overlying the resilient pads 61. As the heating bar 88 and pressure shoe 89 are heated under the influence of the electric heating units 90, the adjacent laminations of the containers are fused or sealed together with a subatmospheric pressure or vacuum condition existent within the filled containers. At the termination of the container sealing operation viz., while roller 148 is in contact with surfaces 156, 157, the roller 190 engages another arm or projection on the Geneva wheel 194 to move valve 79 through an angular distance of 90 degrees. This movement of the valve interrupts the vacuum condition in the tube 73, head 29 and mold blocks and vents the tube and head to the atmosphere so as to eliminate the vacuum previously formed therein by equalizing the pressure within the chamber in the head. At this point the cam surface 155 engages the cam follower 148, and through the medium of rods 21 and 22 and the mechanism connecting said rods to the lever 163, the head 29, bridge member 25 and sealing bar carried thereby are moved to their upper-most or initial positions. The microswitch 130 maintains the motor 111 in operation until after the head 29 has been returned to normal position at which time the microswitch 130 is disconnected by reason of the movement of disc 127 bringing the dwell 129 into juxtaposition with roller 134 associated with the microswitch and break or interrupt the motor circuit.

During the period in which the foregoing sequence of operations is carried on by the apparatus of my invention, the operator is engaged in depositing filled containers in the next succeeding magazine section. At the completion of a cycle of operations of the apparatus as above described, the operator again depresses the foot lever 200, releasing the detent 217 on lever 206 from engagement with recess 216 in disc 215. This action again frees the container carrying magazine so that the operator may manually rotate the magazine through $\frac{1}{2}$ of a revolution in order to bring the next succeeding magazine section 31 into alignment or registration with the vacuumizing and sealing head 29. The cycle of operations previously described is again repeated.

After the magazine section has been moved to a position wherein the sealed containers therein are inclined downwardly, the hinged members 60 and 63 are opened by gravity and the vacuumized and sealed containers fall from the magazine sections to be subsequently conveyed to a packing station. In the event that an abnormal condition is encountered in operating the apparatus, and the motor stopped by an overload switch contained in box 254, the operator may depress the emergency switch 268 to start the motor.

It is apparent that, within the scope of the invention modifications and different arrangements may be made other than is herein disclosed, and the present disclosure is illustrative merely, the invention comprehending all variations thereof.

What I claim is:

1. An apparatus for closing containers including a frame; a magazine having a plurality of sections arranged in fixed relationship and supported upon a rotatable shaft for movement about a horizontal axis; each of said magazine sections being formed with a plurality of chambers adapted to receive and accommodate containers to be closed; means for indexing the magazine to several positions; a head movably mounted upon said frame; means for moving said head into engagement with a magazine section in alignment therewith; means for establishing a differential pressure in said head and effective in said chamber and container disposed therein; a container closing shoe associated with said head; means operable upon said shoe for moving the latter into engagement with a container while said differential pressure is effective upon the container; said head adapted to be disengaged from a magazine section after completion of a container closing operation, and means for releasing the magazine whereby the latter may be moved to bring another section thereof into registration with said head.

2. An apparatus for sealing flexible containers including a frame; a magazine formed with a plurality of radially disposed sections journaled upon a single rotatable shaft for movement about a horizontal axis; each of said magazine sections being formed with chambers each chamber adapted to receive and accommodate a flexible container; a head movably mounted upon said frame; means for moving said head into engagement with a magazine section in alignment therewith; means for establishing a differential pressure in said head and effective in said chamber and container disposed therein; a sealing shoe associated with said head; means operable upon said shoe for moving the latter into sealing engagement with a container while said differential pressure is effective upon said container; said head adapted to be disengaged from a magazine section after completion of a container sealing operation, and means for releasing the magazine whereby another section thereof may be successively moved into registration with said head.

3. An apparatus for extracting air from and closing containers including, in combination, a frame; a rotatable shaft mounted horizontally upon said frame, means mounted upon said shaft and adapted to support a plurality of containers; said containers revoluble about said horizontal shaft; means including a head arranged for periodic movement into engagement with said container supporting means; means for establishing an hermetically tight connection between

said container supporting means and said head; means acting through said head for establishing a subatmospheric pressure upon containers carried by said container supporting means, and means rendered effective during the existence of subatmospheric pressure in said containers and actuated into operation by a predetermined degree of subatmospheric pressure for hermetically closing the containers to maintain a subatmospheric pressure therein.

4. An apparatus for performing closure operations upon containers comprising a frame; a rotatable shaft mounted horizontally upon said frame; a magazine adapted for receiving and supporting containers mounted upon said shaft; said container carrying magazine being revoluble about a single axis formed by said shaft; said magazine being formed with radially arranged chambers adapted for receiver containers; means periodically movable into engagement with the magazine and adapted to establish a hermetically tight connection with said magazine; means for impressing differential pressure in the containers disposed in said magazine, and means for closing the containers in said magazine chambers while said containers are under the influence of differential pressure.

5. Apparatus for hermetically sealing and packaging commodities including a vertical supporting frame; a container carrying magazine mounted upon said frame and arranged for revoluble movement about a horizontal axis, said magazine having radially arranged sections, each section being formed with a plurality of chambers each adapted to receive a container; a movable head mounted upon said frame; said magazine being arranged whereby the sections thereof may be consecutively brought into registration with said head; means for periodically causing inter-engagement between said head and a magazine section to provide a hermetically tight joint; means acting through said head and effective in the chamber of a section in alignment with the head for establishing a subatmospheric pressure in said chamber; means rendered effective while said chamber is subjected to subatmospheric pressure for sealing a container in said chamber whereby a subatmospheric pressure is maintained in the container, and means for equalizing the pressure in said chamber after the completion of a container sealing operation.

6. Apparatus for hermetically sealing and packaging commodities including a supporting frame; a container carrying magazine mounted upon said frame and arranged for revoluble movement about a horizontal axis, said magazine having radially arranged and circumferentially spaced sections, each section being formed with a plurality of chambers, each chamber adapted to receive a container; a movable head mounted upon said frame; said magazine being arranged whereby the sections thereof may be consecutively brought into registration with said head; means for periodically causing inter-engagement between said head and a magazine section to provide a hermetically tight joint; means acting through said head and effective on the chamber of a section in alignment with the head for establishing a subatmospheric pressure in said chamber; means rendered effective while said chambers are subjected to subatmospheric pressure for sealing a plurality of containers in said chambers whereby a subatmospheric pressure is thereby maintained in the containers; means for

equalizing the pressure in said chambers after the completion of the container sealing operation; and electrically driven means for initiating the impression of subatmospheric pressure upon the containers and actuating said container sealing means.

7. In combination, a frame; a horizontal shaft mounted in said frame; a magazine revolvably mounted with said shaft; said magazine being formed with a plurality of radially arranged sections; said sections arranged with a plurality of chambers; said magazine being mounted whereby the same is arranged for movement to bring the chambers of a section successively to a vacuumizing station; means including a head arranged for movement into and out of engagement with one of said sections; cam means for actuating said head, and electrically operated means for driving and controlling the movement of said cam means.

8. In combination, a frame; a magazine revolvably mounted on a horizontal shaft rotatably mounted on said frame; said magazine being formed with a plurality of radially arranged sections; said sections arranged with a plurality of chambers adapted to receive containers to be sealed; said magazine being mounted whereby the same is arranged for movement to bring the chambers successively to a vacuumizing station; means including a head arranged for movement into and out of engagement with one of said sections; cam means for actuating said head; electrically operated means for driving and controlling the movement of said cam means; means for impressing a subatmospheric pressure upon said chambers and containers, and pressure-responsive electrically-actuated means for controlling the duration of subatmospheric pressure on the chambers.

9. In combination, a frame; a horizontal shaft mounted on said frame; a magazine having a plurality of sections; said sections having compartments formed therein; a head movably mounted upon said frame; said magazine being arranged for relative movement whereby said sections may be consecutively brought into registration with said head; cam means for periodically moving said head vertically into engagement with one of said sections; means for impressing a subatmospheric pressure in said head and the compartment in said magazine in registration with said head; a container sealing means associated with said head; said sealing means arranged to be brought into engagement with a container in a compartment of said magazine while the latter is under the influence of subatmospheric pressure; said container sealing means arranged to be actuated by said cam means, and electrically actuated means for controlling the operation of said cam means.

10. Apparatus for vacuumizing and sealing flexible containers comprising in combination a frame; a magazine mounted upon a horizontal, rotatable shaft mounted in said frame and arranged for relative movement; means for moving said magazine to several positions; means for locking the magazine in each such position; means for releasing said locking means whereby the magazine may be consecutively moved to several positions; said magazine having a plurality of sections; said sections having a plurality of chambers; means including a head reciprocable upon said frame and arranged for periodic engagement with said sections; means acting through said head for impressing a sub-

atmospheric pressure in the compartment in said magazine in registration with said head; a heated container-sealing element associated with said head and adapted to be moved into engagement with a container in a chamber for hermetically sealing said container while the latter is under the influence of subatmospheric pressure, and pressure responsive means controlled by the degree of subatmospheric pressure impressed in the magazine compartment for initiating the actuation of the sealing bar toward sealing position.

11. Apparatus for vacuumizing and sealing flexible containers comprising in combination a frame; a magazine mounted upon a horizontal shaft mounted in said frame and arranged for relative movement; said magazine being arranged with a plurality of sections and arranged for movement to several positions; means for indexing and locking the sections in each such position; means under control of the operator for releasing said locking means whereby the operator may move said section to successive positions; said section having a plurality of chambers; means including a head reciprocable upon said frame and arranged for periodic engagement with said section; means acting through said head for impressing a subatmospheric pressure in the compartment in said section in registration with said head; a container sealing element associated with said head and adapted to be moved into engagement with a container in a chamber for hermetically sealing said container while the latter is under the influence of subatmospheric pressure; pressure responsive means controlled by the degree of subatmospheric pressure impressed in the magazine compartment for initiating the actuation of the sealing bar toward sealing position, and means for equalizing the pressure in said magazine compartment after each container sealing operation has been completed.

12. An apparatus for closing containers, in combination, a frame having a pair of spaced upwardly extending portions; a relatively movable head; means associated with said frame portions for supporting said head; a horizontally arranged shaft supported by said frame; a container carrying magazine movably supported upon said shaft and having sections arranged to be successively moved into registration with said head; means for indexing said sections in the several positions; means for releasing said indexing means whereby said sections may be moved to succeeding positions; means for moving said head into engagement with said sections; means for establishing a subatmospheric pressure through said head to containers in one of said sections; means for closing containers while the latter are under the influence of subatmospheric pressure, and electrical circuit closing means set into operation by movement of the magazine to an indexed position for initiating the establishment of subatmospheric pressure to the magazine and actuating the container closing means.

13. An apparatus for closing containers, in combination, a frame having a pair of spaced upwardly-extending portions; a horizontal shaft mounted upon said frame; a relatively movable head; means associated with said frame portions for supporting said head; a container carrying magazine movably supported upon said shaft and having sections arranged to be successively moved into registration with said head; means for indexing said magazine in its several posi-

tions; means for releasing said indexing means whereby said magazine may be successively moved to several positions; means for moving said head into engagement with the magazine; means for establishing a subatmospheric pressure through said head to containers in a section; means for closing containers while the latter are under the influence of subatmospheric pressure; electrically operated means set into operation by movement of the magazine to an indexed position for actuating said head into engagement with the magazine for initiating the establishment of subatmospheric pressure to the magazine and moving said container closing means to container closing position, and pressure-responsive circuit controlling means intercalated with said electrically operated means for establishing a circuit through said latter means to actuate said container closing means when a predetermined degree of subatmospheric pressure has been attained in the containers in said magazine.

14. Apparatus for sealing containers, in combination, a frame having a pair of spaced upright members; a pair of rods reciprocably mounted on each of said upright members; a head member mounted upon said rods and arranged for limited relative movement with respect thereto and to be moved thereby; a container sealing member carried by said head member and associated with said rods arranged to be moved thereby; a container carrying magazine having a plurality of sections, said sections having a plurality of chambers formed therein arranged to accommodate containers to be sealed; means for establishing a subatmospheric pressure through said head member effective in a plurality of chambers of a section in registration with said head; said magazine being arranged for relative movement whereby said chambers of a section may be successively moved into registration with said head member; means for indexing said magazine in its several positions; means for releasing said indexing means whereby said magazine may be moved to its next successive position; means for moving said rods to bring said head member into engagement with the magazine; means arranged to periodically move said container sealing member into sealing engagement with containers disposed in chambers of a section; said rod-actuating means being set into operation by movement of said magazine from one position to its next succeeding position.

15. Apparatus for sealing containers, in combination, a frame having a pair of spaced upright members; a pair of rods reciprocably mounted on each of said upright members; a head member mounted upon said rods and arranged for limited relative movement with respect thereto and to be moved thereby; a container sealing bar member associated with said rods arranged to be moved thereby; a container carrying magazine having a plurality of sections, said sections having a plurality of chambers formed therein arranged to accommodate containers to be sealed; means for establishing subatmospheric pressure through said head member effective in a plurality of chambers of a section in registration with said head; said section being arranged for relative movement whereby said chambers may be successively moved into registration with said head member; means for indexing said magazine in its several positions; means under control of the operator for releasing said indexing means whereby said magazine may

be moved to its next successive position; electrically actuated means for moving said rods to bring said head member into engagement with a section; means arranged to periodically move said container sealing bar member into sealing engagement with a plurality of containers disposed in chambers of a section; said electrically actuated means being set into operation by movement of said magazine from one position to its next succeeding position.

16. In combination, a frame, a plurality of rods reciprocably mounted on said frame; a head member mounted upon said rods and arranged for limited relative movement with respect thereto and to be actuated thereby; a container sealing member associated with said rods arranged to be moved thereby; a container carrying magazine having a plurality of chambers formed therein arranged to accommodate containers to be sealed; said magazine being arranged for relative movement whereby said chambers may be successively moved into registration with said head member; means for establishing a subatmospheric pressure through said head member effective in the chamber in registration with said head; cam-actuated means for reciprocating said rods to move both said head member and said sealing member; means for indexing said magazine in its several positions; electrically-actuated means for operating said cam means; a control switch for said electrically actuated means; said control switch adapted to be moved to operative or nonoperative position by means associated with said magazine; said control switch adapted to be closed to energize said electrically-actuated means upon movement of said magazine from one position to a succeeding position, and means for effecting a release of said indexing means after the containers in a magazine chamber have been sealed by said container sealing member.

17. In combination, a frame having a pair of spaced upright portions; a rod reciprocably mounted on each of said upright portions; a head member mounted upon said rods and arranged for limited relative movement with respect thereto and to be actuated thereby; a container sealing bar associated with said rods arranged to be moved thereby; a container carrying magazine having a plurality of chambers formed therein arranged to accommodate containers to be sealed; means for establishing a subatmospheric pressure through said head member effective in the chamber in registration with said head; said magazine being arranged for relative movement whereby said chambers may be successively moved into registration with said head member; cam-actuated means for reciprocating said rods to move both said head member and said sealing bar; means for indexing said magazine in its several positions; electrically-actuated means for operating said cam means; a control switch for said electrically actuated means; said control switch adapted to be moved to operative or nonoperative position by means associated with said magazine; said control switch adapted to be closed to energize said electrically-actuated means upon movement of said magazine from one position to a succeeding position; and means under control of the operator for effecting a release of said indexing means whereby said magazine may be moved to a succeeding position.

18. An apparatus for sealing containers while under the influence of substantial vacuum comprising, in combination, a frame; pairs of spaced

rods reciprocably mounted upon said frame; a head member mounted upon said rods and arranged to be actuated thereby and to have limited relative movement with respect thereto; a sealing bar carried by said rods; means for heating said bar; a magazine formed with chambers adapted to receive containers movably supported upon said frame; said magazine being arranged to be moved into successive positions to bring the chambers of the magazine into registration with said head member; means for actuating said rods to move said head member into registration with the magazine; means for establishing a substantial vacuum in the chamber in registration with head and effective upon the containers therein; said rod-actuating means being arranged to move said sealing bar into engagement with said containers for sealing the latter while said containers are under the influence of substantial vacuum; means for indexing the magazine in its several positions whereby said chambers therein are successively brought into registration with said head member; electrically-actuated means for actuating said rod actuating means; means set into operation by an indexing movement of said magazine for initiating the container vacuumizing and sealing operations, and means for releasing said indexing means for subsequent movement of said magazine.

19. An apparatus for sealing containers while under the influence of a substantial vacuum comprising, in combination, a frame; pairs of spaced rods reciprocably mounted upon said frame; a head member mounted upon said rods and arranged to be actuated thereby and to have limited relative movement with respect thereto; a sealing bar within said head member carried by said rods; means for heating said bar; a magazine

formed with sections having chambers adapted to receive containers movably supported upon said frame; said magazine being arranged to be moved into positions to bring the chambers of the magazine into successive registration with said head member; cam means for actuating said rods to move said head member into registration with the magazine; means for establishing a substantial vacuum in the chambers of a section in registration with said head and effective upon the containers therein; cam means being arranged to move said sealing bar into engagement with a plurality of containers of a section for sealing said containers while said containers are under the influence of substantial vacuum; means for indexing the magazine in its several positions whereby said chambers of a section are successively brought into registration with said head member; electrically actuated means for operating the cam means which operate said rods and said sealing bar; means set into operation by an indexing movement of said magazine for initiating the container vacuumizing and sealing operation, and means under control of the operator for releasing said indexing means for subsequent movement of said magazine.

THEODOR M. REIMERS.
